MACHINE FOR APPLYING SLIP COVERS TO CONTAINERS

John F. Price, Fulton, N. Y., assignor to Oswego Falls Corporation, Fulton, N. Y., a corporation of New York

Application June 23, 1939, Serial No. 230,825

6 Claims. (Cl. 226—80)

This invention relates to a machine for applying slip covers to containers. The machine is intended particularly for the application of slip covers formed of fibrous material, such as paper-board, to containers formed of like material. The slip covers comprise a discoidal portion and a cylindrical depending flange portion. Covers of this type are disclosed in Patents 2,033,889 and 2,073,537 to L. E. LaBombard.

The invention has as an object a machine of the type described embodying a particularly simple and efficient mechanism embodying a compact, simplified construction rendering the machine suitable for use in small retail establishments where containers are covered only occasionally.

The invention has as a further object a machine of the type described, the entire mechanism of which is operated by a single operating member and which is operable to apply the slip cover to the container without the clerk or operator handling, or otherwise touching, the cover.

The invention has as a further object a construction by which the covers are arranged in stack formation and including mechanism operable automatically to effectively separate the lowermost cover in the stack formation from the covers next above and permit the positive feed of the separated cover to the applying head of the machine.

The invention consists in the novel features and in the combinations and constructions hereinafter set forth and claimed.

In describing this invention, reference is had to the accompanying drawings in which like characters designate corresponding parts in all the views.

Figure 1 is a side elevational view of a machine embodying my invention.

Figure 2 is a top plan view of the machine illustrated in Figure 1.

Figure 3 is a lengthwise sectional view of the machine taken on line 3—3, Figures 2 and 4.

Figure 4 is a transverse sectional view taken on line 4—4, Figure 2.

Figure 5 is a reduced inverted plan view of the machine, partly in section, taken on approximately line 5—5, Figures 3 and 4.

The machine comprises a frame in the nature of a base plate 10. A rib 11 extends upwardly from the base 10, slightly to one side of the center thereof, and extends from the rear end of the base forwardly terminating an appreciable distance from the forward end of the base. The forward portion 12 of the base plate forms a con-

tainer support having a pair of rearwardly converging ribs 13 which function to position the container centrally below the cover applying head of the machine. The rib 11 is formed with a plate 14 which extends laterally at one side of the rib 11 and is further supported by a pair of webs 15.

The frame further includes a top plate 17 formed with an upwardly extending cylindrical portion 18 in which is arranged a chute or hopper 19 to receive the covers in stack formation. The top plate 17 is mounted upon the plate 14, as by screws 20, and the plates 14, 17 are formed with confronting grooves to form a slot 21 extending radially from the cylindrical portion 18. The cap applying head 22 is slidably mounted in an arm 24 extending forwardly from the cylindrical portion 18. The head 22 is of general cylindrical formation with a rear flat side 26 arranged adjacent the forward end of plate 14 and provided with a rectangular aperture 27 through which the covers are fed into the head. The head 22 is slidably mounted upon a stem 28 which, in turn, is slidably mounted in an aperture in the forward end of arm 24. The upper portion of stem 28 is encircled by a helical compression spring 29 which acts between the top of the arm or bracket 24 and a washer 30 secured to the upper end of the stem 28, as by a screw 31. The lower end of the stem is formed with an enlarged head portion 32 which acts as a presser foot to press the cover onto the container when the stem 28 is moved downwardly. The lower edge of the head is beveled, as at 33, to assist centering the container and slip cover.

The covers are successively moved from the bottom of the stack formation into the head 22 by a shuttle or feed member 34 which is slidably mounted between the plates 14, 17 and 36, 17. The plate 36 is secured to the under side of the top plates 17 as by screws 37, and is separated therefrom by a spacer 38. That is, the plate 36 is carried by that portion of the plate 17 extending from the side of rib 11 opposite to the flange 14. This portion of the plate 17 is carried by the cylindrical portion 18. The right and left portions of the plate 17 are arranged in spaced apart relationship to provide a slot to slidably receive the upper narrow portion 39 of the slide 34. The slide 34 is supported by the inner confronting portions of the plates 14, 36, and the slide 34 is guided at its edges by the confronting edges of the spacer plates 14, 17 and 38.

The slide 34 is formed with a depending boss 40 formed with a rectangular slot 41 extending

upwardly from the lower end thereof to slidably receive the crank pin block 42 mounted upon crank pin 43 extending transversely of the base 10 from the lower end of the crank arm 44 which is pivoted on a bracket 45 extending outwardly from the cylindrical portion 18. The crank is also provided with an upwardly and forwardly extending arm 46 provided at its outer end with an operating handle 47 and intermediate its ends with a boss 48 arranged to engage the top of the stem 28 when the handle 47 is moved downwardly. The forward arm 46 of the crank is normally maintained in up position by a tension spring 49 secured at one end to a rearwardly extending projection 50, and at the opposite end to the base plate 10, as by a clamp 51.

Accordingly, when the arm 46 is moved downwardly, the slide 34 is moved rearwardly away from the head 22, and upon engagement of the boss 48 with the upper end of the stem 28, the presser foot 32 is moved downwardly and the head 22 follows until the lower edge 33 engages the upper edge of the container. Further downward movement of the stem 28 effects movement of the cover out of the head 22 and presses the cover onto the top of the container. The cover is frictionally held in the head 22 by a pair of collar engaging members 54 arranged in slots 55 formed in the periphery of the head. The members 54 are yieldingly urged inwardly by springs 56.

Due to the fact that the slip covers are formed with depending cylindrical flanges of appreciable depth, considerable difficulty is experienced in separating the lowermost cover of the stack formation with any conventional cover or cap feed mechanism. The slip covers are formed with a cylindrical depending flange. When the covers are arranged in stack formation, the flange of each cover tends to encircle the top of the cover below. This action makes it difficult to slide the bottom cover from the stack.

My invention includes mechanism for effecting the positive separation of the lowermost cover. This mechanism comprises a cover gripping mechanism arranged in juxtaposition to the lowermost cover of the stack formation, and a second cover gripping means arranged in juxtaposition to the cover next above the lowermost cover. The invention also includes means operable to successively actuate these mechanisms during reciprocation of the cover shuttle 34.

The mechanism for gripping the lowermost cover consists of members 60, 61 slidably mounted between the plates 14, 17 and 36, 17 respectively, and being movable transversely of the cylindrical portion 18. The inner ends of the members 60, 61 are formed of one or more barbs 63 which, upon inward movement of the members 60, 61, engage the flange of the lowermost cover and retain it from upward or axial movement. The inner ends of the slides 60, 61 are provided with end portions 64 extending beneath the slide 34. These end portions are chamfered on their front and rear edges, as at 65, see Figure 5, and are actuated laterally by a cam block 66 secured to the under side of slide 34, as by screws 67. In order to obtain sliding movement of the members 60, 61 in proper timed relation to movement of slide 34 at each end of the stroke thereof, the cam block 66 is formed with an elongated slot 68 to receive each of the screws 67. Also, the forward edge of the boss 48 is formed with a cam surface 69, as indicated by dotted outline

Figures 3 and 5. The slides 60, 61 are urged inwardly by springs 70. The inner end portions 64 for simplicity in manufacture of the machine may constitute separate pieces joined to the slides 60, 61 by intermediate pieces, the members 60, 61 being welded to the respective intermediate members adjacent the outer ends thereof and the inner end members 64 being welded to the inner ends of the intermediate pieces. This structure is shown in Figure 4.

The arrangement is such that when the slide 34 is moved to the end of its stroke rearwardly, the cam block 66 is moved out of engagement with the ends 64 of slides 60, 61, and the slides are moved inwardly under the influence of the springs 70, and the barbs 63 move into engagement with the lowermost cover. When the slide 34 is moved forwardly toward the head 72, the forward end of cam block 66 engages the ends 64, and after the slide 34 is moved a sufficient distance to take up the lost motion resulting from the elongated slot 68, the ends 64 and the slides 60, 61 are moved outwardly thus releasing the cover. The cam block 66 is of sufficient length to hold the slides 60, 61 outwardly until the lowermost cover has been moved an appreciable distance out from under the stack formation.

The mechanism for elevating the stack formation out of engagement with the lowermost cover consists of a pair of cover grippers 72, each being secured to the end of an arcuate shaped arm 73, as by screws 74. The rear ends of the arm 73 are each secured to a spring 75, the opposite end of which is pivotally secured to a block 76 as by screws 77. The block 76 is secured to the top plate 17, as by screws 78. Accordingly, the cover gripping members 72 are movable transversely of the member 18 and also axially thereof.

The gripping members are urged downwardly by a compression spring 80 encircling a stud 81 screwed into the top plate 17, the spring 80 acting against a yoke 82 extending transversely over both of the springs 75. The gripper members 72 are moved laterally by a cam block 83 secured to the upper side of the slide 34 and having rearwardly extending converging sides 84. The forward portion of the cam block 83 is formed with a pair of inclined cam surfaces 85 extending upwardly and rearwardly. The cam surfaces 84, 85 are engaged by a pair of pins 86 secured in the rear end of the arms 73 and depending downwardly toward the slide 34. As the slide is moved rearwardly, the pins 86 are engaged by the cam surfaces 84 and moved outwardly, thus moving the grippers 72 out of engagement with the covers until the cam surfaces 85 pass rearwardly of the pins, at which time the pins are permitted to move inwardly against the ridge 88 separating the cam surfaces 85 and extending to an arcuate cover pusher 89.

At this time, the cover pusher 89 is arranged back of the rear side of the cylindrical member 18, and the covers in the stack formation are permitted to drop upon the plate 17. When the slide 34 is moved forwardly, the pins 86 ride upwardly on the cam surfaces 85, and the cover next above the lowermost cover is thus moved axially upwardly, the pins 86 continuing to travel on the upper surface of the cam block 83 for an appreciable distance. During these movements, the cam block 66 is positioned behind the inner end 64 of the slides 60, 61, whereby the lowermost cap is engaged by the barbs 63. However, as the cover pusher 89 engages the rear side of the lowermost cover, the forward end

of cam block 66 engages the inner end 64 of the slides 60, 61, and effects a spreading action of the same, thereby releasing the lowermost cover. This cover is then moved forwardly by the slide 34, and when it has traveled an appreciable distance out from in under the stack formation, the pins 86 pass off from the tapering cam block 83 and descend to the top of the slide 34. After the slide 34 has completed its forward stroke and approached the end of the rearward stroke, this operation is repeated. Accordingly, the lowermost cover is effectively and positively separated from the cover next above it.

It will be observed that the machine described embodies a particularly simple and compact structure which renders the machine particularly suitable for retail store use, and the machine is operable to effectively apply the slip covers to the containers without the necessity of the covers being handled by the clerk.

What I claim is:

1. A machine for applying slip covers to containers comprising a frame, means for supporting a plurality of said covers in stack formation, a container support, a cover applying head slidably mounted in the frame and operable to apply a cover positioned therein to a container on said support, a shuttle slidably mounted in the frame below said stack formation and operable upon movement toward said head to transfer the lowermost cover of said stack formation to said head, cover gripper members arranged adjacent the bottom portion of said stack formation and being movable radially thereof into and out of engagement with the cover next above the lowermost cover of said stack formation, cam means carried by said shuttle and being cooperable with said gripper members upon axial movement of said shuttle to move said gripper members into engagement with the cover next above said lowermost cover and move the same upwardly out of engagement with said lowermost cover and to subsequently release said upper cover upon transfer of said lowermost cover from said stack formation.

2. A machine for applying slip covers to containers comprising a frame, means for supporting a plurality of said covers in stack formation, a container support, a cover applying head slidably mounted in the frame and operable to apply a cover positioned therein to a container on said support, a shuttle slidably mounted in the frame below said stack formation and operable upon movement toward said head to transfer the lowermost cover of said stack formation to said head, cover gripper members arranged in juxtaposition to the bottom of said stack formation, a cam surface carried by said shuttle and being cooperable with said gripper members upon movement of said shuttle to move said members into engagement with the cover next above the lowermost cover of said stack formation, said shuttle being provided with a second cam surface cooperable with said gripper members while in engagement with said upper cover to move the same upwardly, one of said cam surfaces being cooperable with said members to move the same out of engagement with said upper cover upon transfer of the lowermost cover from said stack formation.

3. A machine for applying slip covers to containers comprising a frame, means for supporting a plurality of covers in stack formation, a container support, a head slidably mounted in the frame, said head being operable to apply a

cover positioned therein to a container on said support, cover gripper members arranged in juxtaposition to the bottom of said stack formation, means operable to cause said members to hold the lowermost cover of said stack formation from axial movement and to move the cover next above said lowermost cover out of engagement with the same and to subsequently release said lowermost cover, a shuttle slidably mounted in the frame and operable to transfer said released cover into said applying head, and means operable during movement of said shuttle to cause said gripper members to release said upper cover.

4. A machine for applying slip covers to containers comprising a frame, means for supporting a plurality of said covers in stack formation, a container support, a cover applying head slidably mounted in the frame and operable to apply a cover to a container on said support, a shuttle slidably mounted in the frame, said shuttle being arranged below said stack formation and being operable to transfer the lowermost cover thereof into said head, a first cover gripper member arranged in juxtaposition to the lowermost cover in said stack formation, a second cover gripper member arranged in juxtaposition to the cover next above said lowermost cover, and means cooperable with said shuttle and said gripper members during movement of said shuttle to cause said first gripper member to successively grip said lowermost cover, hold the same from axial movement and thereafter release the same and to cause said second gripper member to move the cover next above said lowermost cover axially while said lowermost cover is held by said first gripper, and to subsequently release said upper cover.

5. A machine for applying slip covers to containers comprising a frame, means for supporting a plurality of covers in stack formation, a container support, a cover applying head slidably mounted in the frame and operable to apply a cover to a container on said support, a shuttle slidably mounted in the frame below said stack formation and operable to transfer the lowermost cover of said stack formation into said head, a pair of cover gripper members arranged in the frame adjacent the bottom of said stack formation and being radially movable into and out of engagement with the lowermost cover in said stack formation, a second pair of cover gripper members arranged above said first members and being movable radially of said stack formation into and out of engagement with the cover next above said lowermost cover, motion transmitting means cooperable with said shuttle and said gripper members during movement of said shuttle to successively move said first gripper members into engagement with the lowermost cover, move said upper gripper members into engagement with the cover next above said lowermost cover, and move the same upwardly, cause said first gripper members to release said lowermost cover and to subsequently cause said upper gripper members to release said upper cover.

6. A machine for applying slip covers to containers comprising a frame, a container support, a head slidably mounted in the frame and operable to apply a slip cover positioned in said head to a container on said support, means carried by the frame for supporting a plurality of slip covers in stack formation, a shuttle slidably mounted in the frame transversely across

the bottom of said stack formation, said shuttle being movable across the bottom of said stack formation toward said head to transfer the lowermost cover of said stack formation into the head, upper and lower cover gripper members arranged adjacent the bottom of said stack formation, means yieldingly urging said lower members into engagement with the lowermost cover of said stack formation and said upper members into engagement with the cover next above said lowermost cover, a cam member arranged on the under side of said shuttle and cooperable with said lower members to cause the same to engage said lowermost cover when said shuttle is in returned position, a cam mem-

ber arranged on the upper side of said shuttle and cooperable with said upper gripper members to cause the same to engage the cover next above said lowermost cover and remove the same upwardly out of engagement with said lower cover previous to movement of the same by said shuttle upon the forward stroke thereof, said lower cam member being operable to subsequently move said lower gripper members out of engagement with said lower cover, and said upper cam member being operable to move said upper grippers out of engagement with said upper cover upon transfer of said lower cover from said stack formation.
